ELECTRIC STEAMING IRON

Henry V. Ekstedt, St. Louis, Mo., assignor to
Ernest F. Pohl, St. Louis, Mo.

Application June 21, 1939, Serial No. 280,340

12 Claims.

(Cl. 38—77)

This invention relates to certain new and useful improvements in electric streaming irons, the peculiarities of which will be hereinafter fully described and claimed.

5 This application refers to improvements over my prior application on Electric streaming iron, Serial No. 265,807, filed April 3, 1939.

The main objects of my present invention are to provide means to facilitate construction and 10 improve effectiveness of my said prior invention and have special reference first to securing the sole plate to the main body of the iron; second to means for obstructing the water splashed up from below and tending to pass through the vent 15 hole 17 in the horizontally disposed plate; third for providing an independently mounted tube in place of the casting having the passage 12 for delivering steam from above the shelf 16 to the point of the iron; fourth for means facilitating 20 the discharge of steam through the sole plate in place of the vertical openings in the sole plate marked 7 in the prior application; fifth for an improved cover plate in the top of the iron over the steam trap; and to the points of construction 25 and function hereinafter fully described and claimed.

In the accompanying drawing on which like reference numerals indicate corresponding parts:

Fig. 1 represents a sectional view of an electric streaming iron having improvements exemplifying invention;

Fig. 2, a plan view of my iron represented in Fig. 1 with the cover plate removed; and

Fig. 2a, a detail reversed plan view of my cover plate.

Referring to the drawing, the numeral 1 designates a curved top and side walls forming a shell having a pointed front end 2 and a square rear end 3, having a base plate 4 to which is fitted a sole plate 5 forming a smoothing iron of the usual triangular or other suitable shape. The front end of the sole plate has a recess 6 for receiving the steam from the water contained in the shell above the base plate 4, and provided 45 with perforations 7' arranged near the point of the sole plate as indicated in Fig. 1. These perforations 7' are slantingly arranged in a circle extending from the recess 6 to a conical opening A in which is fitted a fastening screw B the head 50 of which is set in the conical opening above the inclined perforations 7' and is firmly screwed into the base plate 4. An upward projection 5a from the sole plate makes contact with the base plate in the center of the steam recess 6, and a 55 similar projection 5b making contact with the end

3 at the rear of the iron, is firmly held by said screw L passing through the same as shown in Fig. 1.

Steam is delivered to the recess 6 by an inclined tube C forming the steam passage 12. The 5 bottom end of this tube is screwed into the base plate 4 so that its end will deliver steam into the recess 6. The upper portion of the tube C passes through a shelf partition the end 16 of which is adjacent a depending vertically disposed baffle 15 10 extending across the shell adjacent the end 16 of the shelf partition to deflect the splash water as stated in my prior application. The shelf referred to cooperates with the baffle 15 and the upper portions of the walls of the shell to provide 15 a steam chamber.

The tube C has its upper end D disposed closely adjacent a cover plate E which has on its underside a curved recess F to allow room for entrance of steam into the end D of the tube similar to a 20 steam dome and yet obstruct splash water entering the end D should such water find its way past the baffle 15 and above the shelf. The cover plate has an overhanging or rabbeted edge provided with a gasket G and held in place by screws 25 H to make a tight joint. The vertical baffle 15 is in close contact with the bottom surface of this cover plate.

The prior application described a vent 17 in through the shelf and in front of the steam passage 12. To avoid any splash water passing upward through this opening 17, I provide in the present application a spring cover I inclined 30 closely adjacent to the opening 17 at its forward end extending into a recess i that guards it 35 against undue pressure at its free end, the spring being held at its rear end by a screw J to which access is given when the cover plate E is removed. I provide tapped holes K—K' in front and rear 40 portion of the shell respectively by which a suitable handle is secured to the shell as indicated by dotted lines in Fig. 1.

Besides the fastening screw B before mentioned for the front of the sole plate fastening, I provide 45 said screw L at the rear of the base plate and firmly secured in the rear end of the sole plate adjacent the square end 3. The open recess M in the rear end of the shell back of the rear wall N has suitable electric cord plug connectors O for attachment of the usual plug for the electric wires 50 as described in my prior application.

The rearward recess 8 in the sole plate is provided with a suitable electric heating element 9 connecting to a source of electricity as described in my prior application.

Reference is made to said prior application of mine for other features of construction in this present application that are similar in the two applications but not described or claimed in the present application.

It has been found by actual demonstration that the present improvements facilitate the manufacture and assembling of the various parts, and also increases the effectiveness of my iron in manipulation of the same in the process of using it as a smoothing iron, and in avoiding leakage of the splash water into the passage 12 and undesired exit of said water from the front recess C. The conical recess A with the inclined openings 7' communicating with the steam recess 6, improves the application of the steam to the goods being smoothed by the passage of the sole plate over the same after the application of steam through the described communicating passage 20 7' into the conical chamber A as the iron passes forward and backward over the fabric being smoothed.

The present construction of the passage 12 by means of the independently attached tube C lessens the cost of construction and assembling of the same, and the location of its upper end D close to the cover plate and to the upward recess F, facilitates the entrance of the steam into the end D and also tends to avoid any splash water entering the tube should such water pass 30 over the baffle 15 and gain admittance above the shelf.

It has also been found that the spring cover I obstructs the water that is splashed upward through the opening 17 in the usual, or unusual manipulation of the steam iron.

Referring again to the fastening screws B and L at the front and back ends respectively, it will be seen that the screws pass into solid portions adjacent and that they do not enter or pass through any portion of the water chamber. Thus there is no danger of leakage of water from the chamber through the fastening connections. This is an important feature of my iron.

45 I claim:

1. An electric steaming iron having in combination a shell provided with a base plate, a sole plate below said base plate and having a recess for steam at its forward end at the upper face thereof and said sole plate being provided with a conical recess in the lower face opening outwardly through the pressing surface of the plate and the sole plate having inclined steam exit openings establishing communication between said recesses, and a fastening screw extending upwardly through said conical recess into said base plate.

2. An electric steaming iron including a shell provided with an integral base plate, a sole plate fitted on said base plate, a steam chamber formed between said plates and having an exit through the sole plate to the pressing surface of the iron, and means for securing said plates together consisting solely of two securing screws, one screw at the front end of the iron extending upwardly through the sole plate and having its shank passing through said steam chamber and the other screw at the rear end of the iron and both arranged wholly outside of the interior of said shell, thereby obviating packing between the shell and its base plate and at said securing devices and preventing leakage at such places.

3. An electric steaming iron having in combination a shell forming a water reservoir, a sole plate attached to the shell, a shelf near the top

of the shell at the front end thereof provided with a hole near and spaced from the front thereof adjacent the front end of the iron, means for heating water in the reservoir to generate steam therein, means for conducting steam from above said shelf to and through the sole plate, and a plate mounted between the top of the iron and said shelf adjacent said hole to form a guard to prevent splashing of water through said hole into the inlet end of said steam conducting means.

4. An electric steaming iron having in combination a shell provided with a recess in the front wall thereof, a sole plate attached to the shell, a shelf extending backward near the top 15 of the shell to provide a steam chamber in the upper portion of the shell, said shelf being provided with a hole near the front end thereof, means for heating water in the shell to generate steam therein, means for conducting steam from 20 above said shelf to and through the sole plate, and a spring plate having its front portion inclined over said hole and extending into said recess in the front wall of the shell and having its rear end secured to said shelf and serving as 25 a guard to prevent water splashing to the top of the shell through said hole in the shelf.

5. An electric steaming iron including a hollow body providing a water reservoir, a shoe, a screw for securing the shoe to the hollow body and 30 spaced wholly from and terminating short of the faces of the interior walls of the hollow body, said iron being provided with a steam receiving recess surrounding the screw, means for heating the water in the reservoir to generate steam 35 therein, a relatively small substantially annular group of perforations leading from said steam receiving recess and arranged to discharge steam at the pressing surface of the iron, and means for conducting steam from the reservoir to said 40 recess.

6. An electric steaming iron including a shell provided with an integral base plate and there-with constituting a water tight reservoir and a steam space above the water line, a sole plate 45 fitted to said base plate, one of said plates having a recess in its inner face at the forward end of the iron to provide a relatively small steam chamber between said plates, the steam chamber having communication with the steam space of 50 the water reservoir and also having an annular arrangement of spaced outwardly converging outlets confined in an area smaller than the area of said steam chamber and disposed immediately below said recess and extending through the sole 55 plate from the recess to discharge steam in the immediate vicinity of said small steam chamber, the remainder of the pressing surface, including the central area thereof, being plain, smooth and unbroken whereby to discharge 60 steam from the iron only at the forward end thereof through said converging outlets, and means for heating the water in the reservoir to generate steam therein.

7. An iron of the character described includ-ing a hollow body having a lower pressing sur-face and forming a water reservoir and having a chamber in its upper portion extending rear-wardly from the front end of the iron and hav-ing a relatively small opening in its front por-tion and a relatively large opening in its rear portion, said openings tending to equalize the steam pressure in the chamber with the balance of the pressure in the water reservoir, means for conducting steam from the steam chamber 70

to the pressing surface of the iron, and a shield 5 for said small opening consisting of a plate secured in the chamber and extending over the small opening in spaced relation thereto to prevent water splashing through the small opening into the steam conducting means.

8. An iron of the character described including a hollow body having a lower pressing surface and forming a water reservoir and having a 10 chamber in its upper portion extending rearwardly from the front end of the iron and having a relatively small vent opening in its front portion and a relatively large opening in its rear portion, said openings tending to equalize the steam 15 pressure in the chamber with the balance of the pressure in the water reservoir, means located between said openings for conducting steam from the chamber to the pressing surface of the iron, and a shield located in said chamber above said 20 vent opening and arranged to prevent water splashing through the vent opening into said steam conducting means.

9. An iron of the character described comprising a hollow body forming a water reservoir having a steam space above the normal water level 25 of the reservoir and also having a pressing surface, means to heat water in the reservoir to generate steam therein, a steam chamber disposed in the steam space above the normal water line 30 in the reservoir and confined wholly within the reservoir at the upper front portion thereof, said steam chamber having front and rear openings therein communicating with the reservoir and with the steam space to permit steam to pass from the steam space to said steam chamber, means to 35 conduct steam from the steam chamber to and through the pressing surface, the inlet end of the steam conducting means being arranged between the said openings of the steam chamber, whereby 40 pressures in the reservoir and steam chamber are substantially balanced to prevent syphoning of water from the reservoir to the pressing surface, and means located in the steam chamber in spaced relation with the front opening to prevent 45 water splashing through the front opening into the steam chamber from splashing into the inlet end of said steam conducting means.

10. An iron of the character described comprising a hollow body forming a water reservoir having a steam space above the normal water level 50 of the reservoir and also having a pressing surface, means to heat water in the reservoir to gen-

erate steam therein, a steam chamber disposed in said steam space above the normal water line in the reservoir and confined within the reservoir at the front portion thereof, said steam chamber having front and rear openings therein communicating with the reservoir and with said steam space to permit steam to pass from the steam space to said steam chamber, said front opening being smaller in diameter than the rear opening, means for conducting steam from the 10 steam chamber to and through the pressing surface of the iron, the inlet end of the steam conducting means being arranged between said openings of the steam chamber, and means located adjacent the smaller of said openings in spaced relation thereto to prevent water splashing into the inlet end of said steam conducting means. 15

11. An electric steaming iron comprising a shell provided with a base plate, a sole plate below the base plate, one of said plates having a recess 20 therein at the forward end thereof forming a relatively small steam chamber, the sole plate having a conical recess in its outer face adjacent the steam chamber and also having steam exit openings leading from the steam chamber to the 25 conical recess, and a screw having a tapering head passed through said recesses into the base plate to secure said plates together at the forward end of the iron, the tapering head of the screw being countersunk in the conical recess and lying 30 above the outlet ends of said exit openings.

12. An electric steaming iron including a shell having a base plate and constituting a water reservoir, a sole plate disposed against the base plate of the shell, a relatively small shallow steam 35 chamber formed between said plates at the forward end of the iron, the sole plate having a recess in its pressing surface spaced from and immediately beneath said steam chamber, there being a series of openings arranged in annular 40 formation between said recess and said chamber, a screw having its shank passing through the sole plate centrally of the annular series of openings and connecting the base plate whereby to secure said plates together at the forward end of the 45 iron, means for heating the water in the reservoir to generate steam therein, and means for conducting steam from the reservoir to said steam chamber for discharge through said steam openings to the pressing surface of the iron. 50

HENRY V. EKSTEDT.
